UNITED STATES PATENT OFFICE.

PHILIP MUELLER AND JOHN BOLAND, OF DECATUR, ILLINOIS; SAID MUELLER ASSIGNOR TO H. MUELLER MANUFACTURING COMPANY, OF DECATUR, ILLINOIS, A CORPORATION OF ILLINOIS.

GRINDING OR POLISHING MACHINE.

No. 819,021.

Specification of Letters Patent.

Patented April 24, 1906.

Application filed August 7, 1905. Serial No. 273,174.

To all whom it may concern:

Be it known that we, PHILIP MUELLER and JOHN BOLAND, residents of the city of Decatur, county of Macon, and State of Illinois, 5 have invented certain new and useful Improvements in Grinding or Polishing Machines, of which the following is a specification.

One object of our invention is to provide a 10 shiftable hood which may be moved lengthwise of the suction-pipe to bring the center of the hood in line with grinding or polishing wheels located at different points on the drive-shaft.

Another object is to facilitate exchanging 15 wheels on the shaft without displacing any part of the hood.

Another object is to provide simple and effective means for varying the size of the passage-way from the hood to the suction-pipe, 20 so as to properly distribute the suction among a plurality of hoods, and another object is to improve certain details of the hood.

The invention is exemplified in the structure hereinafter described, and it is defined 25 in the appended claims.

In the drawings forming part of this specification, Figure 1 is a front elevation of a grinding or polishing machine the wheels of 30 which are provided with hoods and adjuncts embodying our invention. Fig. 2 represents a fragment of the suction-pipe, showing a provision for connecting the down-leg of the hood slidably on the pipe. Fig. 3 is a side 35 elevation of an embodiment of our invention. Fig. 4 is a rear view of the hood from the direction shown by the arrow in Fig. 3. Fig. 5 is a perspective representation of the slide used on the foot of the down-leg to vary the 40 passage-way from the hood to the suction-pipe.

A grinding-wheel 1 is shown located close to the journal-box of the drive-shaft on one side of the machine, and a smaller wheel 1^a is 45 shown attached to the projecting end of the shaft on the opposite side of the machine.

The hood comprises an approximately hemispherical shell 2, located behind the wheel, and an approximately horizontal extension 3, which merges with the vertical 50 part and is located beneath the wheel. A narrow groove 4 is formed in the back part of the hood, and a wider conduit 5 conjoins with

the narrow conduit 4 and communicates with the horizontal extension 3. The conduits 4 and 5 converge to the down-leg 6, with which they unite. The lower end of the down-leg is attached to a slide-plate 8, and the connection is strengthened by braces 7. A suction-pipe 9 is adapted to draw off dust from the 60 hoods, and it has a flattened side extension or enlargement for each down-leg, as shown at 10. An elongated opening 12 is formed through the flat surface of the suction-pipe, and the downturned flanges 11 form slide-ways for plate 8 of the down-leg. A plate 14 is placed below plate 8, as shown in Figs. 1 and 3, and it is provided with an opening 16, (shown in Fig. 5,) which is about the same size and shape as the discharge-opening 70 through the down-leg. The plate 14 is longer than plate 8. It is slidable with relation to the plate 8, and it is preferably provided with an upturned flange or ledge 15, by means of which it may be manipulated. 75

Dust formed by the grinding or polishing wheel is projected into the hood by centrifugal force. Some of the particles fall into the horizontal extension 3 and descend through conduit 5 to the down-leg, while other particles are projected into the back part of the hood and drawn into the narrow conduit 4. 80

When the grinding-wheel is set close to the journal-box of the shaft, as shown at the left side of Fig. 1, the slide 8 is in one extreme position of lateral adjustment, and when a wheel is on the end of the shaft away from the boxing, as shown at the right side of Fig. 1, the slide-plate and the hood are moved to the opposite extreme, and the narrow groove 90 or conduit 4 is brought into alignment with the wheel. In shifting the hood the lower end of the down-leg maintains communication with the suction-pipe through the elongated opening 12, and the plate 8 acts as a 95 closure for all of the opening that would otherwise be uncovered.

The opening 16 through plate 14 may be placed in alignment with the down-leg discharge-opening, in which case the passage from the down-leg will be free and unobstructed, or it may be moved to one side to a greater or less extent, so that the solid part of the plate 14 will diminish or entirely cut off the communication between the down-leg 100 and the suction-pipe. This provision is use- 105

ful in controlling the suction in several hoods communicating with the same suction-pipe, as it provides for diminishing the passages leading from hoods nearer the suction, so as to equalize the suction in each of the hoods. It also provides for entirely cutting off suction from wheels not in use.

In Fig. 1 the plate 14 is adjusted on the right side of the machine to leave the communication from the hood to the suction-pipe wide open, and on the left side of the machine the slide is moved to partly close the opening. The plate 14 will ordinarily slide with plate 8 in adjusting the hood laterally on the suction-pipe; but means may be provided for securing the two plates together in any desired correlation.

The approximately hemispherical configuration of the upper part of the hood permits the removal and replacement of a grinding or polishing wheel without removing the hood or any part thereof or without swinging any part of the hood aside, and the contracted conduit 4 intensifies the suction at the back of the hood to catch the particles that would otherwise tend to carry upward over the wheel. A flap 13 may be suitably connected with the hood in any desired position, and it may be swung or otherwise moved nearer to or farther from the wheel, so as to intercept any heavy particle difficult of control by suction.

What we claim as new, and desire to secure by Letters Patent, is—

1. A hood for grinding or polishing wheels, extending behind, below and partly above the wheel, a down-leg leading from the lower part of the hood, and a narrow depression in the back part of the hood extending downward to the down-leg and forming a laterally-contracted conduit.

2. A hood for grinding or polishing wheels, comprising a concave shell in an approximately vertical position, a horizontal extension of the lower part of the shell, a down-leg leading from the lower part of the hood and the extension thereof, and a narrow depression in the back part of the hood extending downward to the down-leg and forming a laterally-contracted conduit.

3. A hood for grinding or polishing wheels, comprising an approximately hemispherical shell extending in a generally vertical direction and merging with a narrower horizontal extension and a down-leg connected with the lower part of the hood.

4. In a grinding or polishing machine, the combination of a horizontal suction-pipe, a grinding or polishing wheel mounted on a shaft parallel with the suction-pipe, an approximately hemispherical hood for the wheel, and a down-leg for the hood communicating with the suction-pipe and slideable lengthwise thereof. 60

5. In a grinding or polishing machine, the combination of a horizontal suction-pipe, a grinding or polishing wheel the axis whereof is parallel with the suction-pipe, a hood for the wheel, a down-leg for the hood, and an elongated foot on the leg slideable lengthwise 70 of the pipe in communication therewith.

6. In a grinding or polishing machine, the combination of a horizontal suction-pipe, a grinding or polishing wheel, a drive-shaft parallel with the suction-pipe and adapted to 75 carry a wheel at different places along its length, a hood for the wheel, a down-leg for the hood and an elongated foot for the leg, slideable lengthwise of the pipe in communication therewith. 80

7. In a grinding or polishing machine, the combination of a horizontal suction-pipe, a grinding or polishing wheel the axis whereof is parallel with the suction-pipe, and an approximately hemispherical hood for the wheel 85 communicating with the pipe and movable lengthwise thereof.

8. In a grinding or polishing machine, the combination of a suction-pipe having a flat side, a dust-collecting hood, a down-leg for 90 the hood, a plate on the lower end of the down-leg slideable on the flat side of the pipe, and an apertured plate slideable between the plate of the down-leg and the flat side of the pipe for controlling the opening between the 95 down-leg and the pipe.

9. In a grinding or polishing machine, the combination of a suction-pipe having an elongated side opening, a dust-collecting hood, a down-leg for the hood, a plate on the 100 lower end of the down-leg slideable on the open side of the pipe, and an apertured plate slideable between the plate of the down-leg and the pipe for controlling the passage-way from the down-leg to the pipe. 105

In testimony whereof we sign our names in the presence of two subscribing witnesses.

PHILIP MUELLER.
JOHN BOLAND.
